US0D1035123S

(12) **United States Design Patent** (10) Patent No.: **US D1,035,123 S**
(45) Date of Patent: ** Jul. 9, 2024

(54) **ELECTRONIC ATOMIZER**

(71) Applicant: **ALD GROUP LIMITED**, Guangdong (CN)

(72) Inventors: **Jia Zhou**, Guangdong (CN); **Ziwei Xu**, Guangdong (CN)

(73) Assignee: **ALD GROUP LIMITED**, Guangdong (CN)

(**) Term: **15 Years**

(21) Appl. No.: **29/889,331**

(22) Filed: **Apr. 11, 2023**

(30) **Foreign Application Priority Data**

Dec. 16, 2022 (CN) 202230844205.3

(51) LOC (14) Cl. **27-02**

(52) U.S. Cl.

USPC **D27/162**

(58) **Field of Classification Search**

(57) **CLAIM**

The ornamental design for an electronic atomizer, as shown and described.

DESCRIPTION

FIG. 1 is a front perspective view of an electronic atomizer showing our design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures depict portions of the electronic atomizer that form no part of the claimed design.

1 Claim, 8 Drawing Sheets
